(57) **CLAIM**

The ornamental design for a console for control coupled with transparent display as shown and described.

DESCRIPTION

1. Console for control coupled with transparent display

1.1 : Front Perspective

1.2 : Front Elevation

1.3 : Rear Elevation

1.4 : Left

1.5 : Right

1.6 : Top

1.7 : Bottom

The broken lines depict portions of the console for control coupled with transparent display that form no part of the claimed design.

The present design is a console which is coupled with a transparent curved display and enables the user to control over IoT while the user sees a peripheral device and a surrounding environment directly.
